UNITED STATES PATENT OFFICE.

BENJAMIN A. J. DYKES, OF GLENWOOD, GEORGIA.

DESIGN FOR A GAME-BOARD.

49,575.

Specification for Design.

Patented Aug. 29, 1916.

Application filed November 20, 1915. Serial No. 62,648. Term of patent 14 years.

To all whom it may concern:

Be it known that I, BENJAMIN A. J. DYKES, a citizen of the United States, residing at Glenwood, in the county of Wheeler and State of Georgia, have invented a new, original, and ornamental Design for Game-Boards, of which the following is a specification, reference being had to the accompanying drawing, forming a part thereof.

The figure is a top plan view of a game board, showing my new design.

I claim:

The ornamental design for a game board, as shown.

BENJAMIN A. J. DYKES.

Witnesses:

A. A. GALBRAITH,
A. F. BEACHAN.
